UNITED STATES PATENT OFFICE.

HENRY N. EDENS, OF NEW HOLSTEIN, WISCONSIN, ASSIGNOR TO THE JOHN LAUSON MANUFACTURING COMPANY, OF NEW HOLSTEIN, WISCONSIN.

ENGINE-STARTER.

1,095,387.

Specification of Letters Patent.

Patented May 5, 1914.

Application filed June 28, 1912. Serial No. 706,438.

To all whom it may concern:

Be it known that I, HENRY N. EDENS, a citizen of the United States, and resident of New Holstein, in the county of Calumet and State of Wisconsin, have invented certain new and useful Improvements in Engine-Starters; and I do hereby declare that the following is a full, clear, and exact description thereof.

10 My invention refers to ignition systems of the magneto type for gas engines, its object being to provide a simple, economical and effective means for positively starting such engines, the same being accomplished by 15 timing the magneto in relation to the sparking moment through a gear train whereby a partial rotation of the engine crank-shaft in a reverse direction from its drive will produce the desired spark at the highest point 20 or "peak of the wave", to produce explosion of a partially compressed initial gas charge.

The essential feature of this invention is, under all conditions, to provide a positive driving means for the magneto at a ratio of 25 2 to 1 relative to rotation of the engine crank-shaft. To obtain the maximum efficiency it is also desirable to employ a low tension alternating magneto of the make and break rotary type, together with means for 30 retarding the spark incidental to starting the engine, and for advancing said spark thereafter when the engine is under normal running conditions.

With the above object in view the invention 35 consists in certain peculiarities of construction and combination of parts as set forth hereinafter with reference to the accompanying drawings and subsequently claimed.

40 The drawing represents a diagram view of a gas engine embodying the features of my invention, parts being in section and other parts broken away to more clearly illustrate structural features.

45 Referring by characters to the drawing, 1 represents the cylinder of a gas engine of the compression type and 2 the explosion chamber thereof, the cylinder being provided with a standard piston 3, which piston is 50 connected to the crank-pin 4 of an engine crank-shaft 4' by a pitman 5 that is illustrated in dotted lines. The explosive chamber of the cylinder is provided with a standard set of intake and exhaust valves (not

shown) and also a make and break mechanism of the hammer type comprising a spring-actuated trip-lever electrode 6, that is adapted to close an electric spark-circuit through contact with a fixed electrode 6', which electrode is insulated from the engine cylinder. The crank-shaft 4' carries a toothed pinion 7, which serves as a driver for a toothed gear-wheel 8, which gear-wheel carries the usual sparking-cam 8', the ratio of the pinion and gear-wheel being 2 to 1 respectively, whereby the sparking-cam is timed to make one revolution to two revolutions of the engine crank-shaft. The spark-cam is adapted to engage and actuate a reciprocal sparking-rod 9 that is supported in suitable bearings, the same being formed in two sections that are in telescopic connection, one of which sections carries a bracket 10, having a sleeve portion through which the other section of the rod is loosely fitted. The bracket carries a cam-slotted timing lever 11, the slot of which engages a pin 12 that extends from that section of the rod which is supported in the bracket. Movement of this cam-lever is adapted to shorten 65 and lengthen the spark-rod, whereby the timing of the spark may be advanced or retarded. The lever is designed to have three distinct movements, in each of which movements it is locked by engagement with 70 notches of a detent 10' that forms part of the bracket 10. Thus the timing lever, as shown in the diagram, is locked in its central or running position, whereby the spark is advanced and when moved to the right the 75 spark is retarded, owing to shortening of the lever of the sparking-rod, while movement to the left will cut out the sparking mechanism. The inner end of the spark rod is provided with an anti-friction roller for engagement with the cam 8' and said roller together with the rod is held in its engaged position by a spring 9'. The outer end of the rod carries a plunger-head 9'', a nose of which is adapted to engage and actuate the trip lever electrode 6, said plunger-head being adjusted with relation to its time of engagement with the lever by a pin 9''' upon which the lower face of said plunger head 80 plays.

Supported by the engine frame is a magneto 13, the armature spindle of which carries a toothed pinion 14, which pinion has

meshing engagement with the gear-wheel 8, the said pinion being of such ratio with relation to the gear-wheel that it will make four revolutions to one of the latter and hence it follows that by the train of driven gears from the crank-shaft the magneto armature is given two complete revolutions to one revolution of said crank-shaft. The magneto shown is preferably of the low tension type and may be of any standard design, the same forming no part of my invention. As shown the magneto spindle also carries an indicator dial 15, the face of which is provided with diametrically opposite indicator points *a*, *a'*. These indicator points in conjunction with a stationary indicator point *b*, upon the face of the magneto, show the positions assumed by the armature at the peak of the wave, in each half revolution thereof instances where the armature is rotating from left to right, as indicated by the arrow on point *b*. When the parts are in the relative positions shown in the diagram the indicator points *a* and *b* are registered and the magneto has developed in its rotation the highest point of the wave. Incidental to the parts assuming this position under normal running conditions, the crank-pin is advanced to approximately its limit on a compression stroke and the spark moment being advanced, a spark will be produced, by action of the cam upon the spark mechanism, causing a break to occur between the electrodes, it being understood that the crank-shaft is rotating from left to right as indicated by the arrow. Hence it will be apparent that with each complete cycle of the crank-shaft, ignition of a gas charge will occur, when the crank assumes the position shown in full lines in diagram, the magneto armature having made two complete revolutions in the meantime and developed four high points in the electric current, only one of which is utilized. In this operation of normal running, the sparking mechanism acts in a similar manner to that ordinarily employed in a magneto system geared in the usual manner, with the exception that in this instance the magneto is geared to rotate at double the speed of that ordinarily used. This higher speed however has no detrimental effects upon the mechanism. The face of the magneto is also provided with a second stationary indicator point *b'*, which point is so positioned relative to the armature of the magneto, as to indicate, in conjunction with the dial indicator points *a*, *a'*, the peak of the wave generated in instances where said magneto armature is rotated from right to left, or in a reverse direction from that ordinarily employed. All of these indicator points form no part of my invention and are commonly utilized in magnetos at the present time. The magneto is also connected in the ordinary manner by

a wire 13' to the stationary electrode 6', the circuit being completed through the engine frame.

The above described mechanism is all of ordinary construction, with the exception that the magneto when embodied in a starter mechanism made in accordance with my invention, in place of being rotated in synchrony with the crank-shaft is so geared up as to make two revolutions to one of the crank-shaft.

In the operation of my device, for example and clearness of illustration, the indicator points *b* and *b'* are spaced apart approximately 30° . Should it be desired to start the engine when the crank-pin 4 is in its normal or advanced position as shown, the timing lever 11 would be moved from left to right, whereby the spark is retarded. The next operation would be to rotate the crank-shaft from right to left, approximately a half turn, to the position indicated by the dotted line *x*, causing the piston to suck in a gas charge. Incidental to this half rotation of the crank the magneto armature will make one revolution from right to left, bringing the dial indicator point *a* again to the position shown in the diagram. The timing cam 8' will, at the same time, be rotated a quarter of a turn, to the point indicated by the dotted line *y* and hence although the magneto has reached the peak of the wave, owing to the position of the timing cam there will be no spark. The operator now reverses the movement of the crank-shaft, rotating it from left to right or from point *x* to point *x'*, as indicated by the radially disposed dotted line. The crank-shaft in this reverse movement travels a quarter of a revolution plus 15° totaling 105° . This movement causes the magneto armature to travel from right to left a half revolution, plus 30° , making a total of 210° , which movement causes the indicator point *a'* to be brought in register with the indicator point *b'*, at the registration of which points the magneto has again reached the peak. Incidental to this reversing movement of the crank-shaft and reverse movement of the magneto, the timing cam will have rotated an eighth of a turn plus $7\frac{1}{2}^\circ$ or a total of $52\frac{1}{2}^\circ$, reaching a point indicated by line *c'*, at which point the timing rod has been thrust forward whereby the spark mechanism is tripped, to cause a break in the circuit at the peak of the wave and an explosion of the partly compressed charge with the result that the engine is started from right to left. The next step is to advance the spark by moving the timing lever 11 to the central position shown in the diagram, whereby the apparatus is in full running position. Thus it is apparent that the starting of the engine can be effected by a reverse movement of the crank, through less

than a half revolution thereof, this movement being the novel feature in the starting operation. It should be understood however, that prior to this reverse movement, should the crank be in the advanced normal position shown, the same must first be rotated approximately a half revolution from right to left to cause movement of the piston, whereby a charge of gas is sucked into the cylinder. Should this charge be in the cylinder however at the time of starting and the engine crank be in the position indicated by dotted line α , only a slight reverse movement, as described, is necessary for starting. It is also apparent that this arrangement of starting mechanism can be utilized to start in the ordinary manner wherein the crank is rotated from right to left continuously to produce a suction stroke of the piston and compression stroke thereof, in which case as a precautionary means the spark moment would be retarded in the usual manner.

I claim:

1. In a gas-engine having a cylinder, a piston therefor, a crank for the piston, a cam-actuated spark-controlling mechanism, and a single-phase magneto; the combination of a one to two back gear connection between the crank shaft and the cam-actuated spark-controlling mechanism, and a two to one accelerated gear connection between the crank-shaft and magneto, the last-mentioned gear connection being arranged to produce a spark at the wave peak upon a reverse movement of the crank shaft to provide a substantially partial compression of a gas charge.
2. In a gas-engine having a cylinder, a piston therefor, a crank for the piston, a cam-actuated spark-controlling mechanism,

and a single-phase magneto; the combination of a one to two back gear connection between the crank-shaft and the cam-actuated spark-controlling mechanism, and a two to one accelerated gear connection between the crank-shaft and magneto, the last mentioned gear connection being arranged to produce a spark at the wave peak upon a reverse movement of the crank shaft to produce approximately a three-quarters compression of a gas charge.

3. In a gas-engine having a cylinder, a piston therefor, a crank for the piston, a cam-actuated spark-controlling mechanism, and a single phase magneto; the combination of a 55
sparking cam and approximately a two to one accelerated gear connection between the crank-shaft and magneto, whereby upon approximately a one-half revolution of the engine shaft to draw in a charge of gas, the 60
sparking cam is located one-quarter of a revolution in a reverse direction, and a complete revolution of the magneto armature from its point of wave peak is effected, and thereafter upon reversal of the engine shaft 65
through approximately 140 degrees to produce compression, the sparking cam is caused to rotate approximately 52 degrees coincident to reverse rotation of the armature through 210 degrees, whereby the same 70
will produce a spark at the peak of the wave.

In testimony that I claim the foregoing I have hereunto set my hand at New Holstein in the county of Calumet and State of Wisconsin in the presence of two witnesses.

H. N. EDENS.
